UNITED STATES PATENT OFFICE.

WALTER O. WILLE, OF WATERLOO, IOWA.

SIGNALING DEVICE FOR VEHICLES.

Application filed November 18, 1921. Serial No. 516,098.

To all whom it may concern:

Be it known that I, WALTER O. WILLE, a citizen of the United States of America, and a resident of Waterloo, Blackhawk County, Iowa, have invented certain new and useful Improvements in Signaling Devices for Vehicles, of which the following is a specification.

My invention relates to improvements in signaling-devices, and particularly to those which are mounted upon vehicles for indicating changes in direction, and the object of my improvement is to supply a collapsible extensible device of this class capable of being extended in different directions as desired to thereby vary the significance of the signal.

Another object of my improvements is to provide means for retracting the index part of the device into a hollow housing, the index being constructed to protect the enclosed mechanism from the action of the elements when so retracted.

These objects I have accomplished by the means which are hereinafter described and claimed, and which are illustrated in the accompanying drawings, in which Fig. 1 is a side elevation, with a part broken away of said signaling device, the full lines indicating one extended position, and the dotted lines indicating other extended positions of the lazy-tongs and index. Fig. 2 is a similar elevation of the device, showing the lazy-tongs and index completely collapsed within the housing. Fig. 3 is a horizontal section taken through the upper part of said Fig. 2.

Similar numerals of reference denote corresponding parts throughout the several views.

The numeral 1 denotes a hollow housing composed of spaced plates connected by battens at top and bottom to leave both ends open. This housing may be fixedly secured upon a relatively immovable part of the vehicle, so I have not shown any special supporting structure in the drawings. Also, a hollow housing is not obligatory as my signaling device may be operably mounted upon a single plate 1 which has suitable slideways or divergent slots upon or in it. These slideways or slots shown at 4 and 5 diverge downwardly from the upper end-part 3 of the medial vertical slot 2 but the upper ends of said slots 4 and 5 enter said slot 2 a little below the top of the latter

which thus provides a medial recess 3 at the top for a purpose to be described. The divergent slots 4 and 5 extend downwardly farther than the middle slot 2, and are preferably of the same length.

The numeral 19 denotes an index preferably made in the outline of a hand, with extended fingers, and comprises spaced plates which are integrally connected along one longitudinal edge opposite the thumb part as also at the terminals of three fingers by a part 20 rigidly. The interspace of these plates receives the outer terminal members 13 and 14 of a lazy-tongs and also a link 17 pivoted to the outer end of the member 13. The other end of this link is pivoted at 18 across the interspace of the plates 19 near the connecting part 20, and the outer end of the member 14 is pivoted at 15 across said plates at a point near the wrist part of the index. The lazy-tongs may be made of any desired number of such members medially pivoted together and having their ends pivoted to the adjacent pairs as at 12 and 16, 80 but I have for convenience shown but two pivotally connected pairs 13-14 and 9-10. The opposite end of said lazy-tongs has the inner extremity of the member 10 permanently pivoted at 11 at a short distance below the middle slot 2 vertically. The inner end of the member 9 is extended inwardly and bent angularly downward to provide the manually operable handle or lever 8, and a roller bearing pintle 7 is projected from the angle of the parts 9 and 8 into said series of slots so as to be movable lengthwise through each at will. A modification is shown in Fig. 3 wherein the lever 8 is dispensed with and the opposite housing plate 1 is provided with like slots 2, 4 and 5, the pintle 7 being extended therethrough and furnished with a handle 21 by which the lazy-tongs may be operated.

Either the lever 8 or the handle 21 may be used in shifting the member 9 by moving its pintle 7 appropriately in any of the slots 2, 4 or 5 to thereby extend or collapse the lazy-tongs in desired directions or hold the lazy-tongs fully collapsed within said housing 1, as shown in Fig. 2. The full lines in Fig. 1 show the lazy-tongs and index fully extended horizontally as when indicating a proposed change of direction of the vehicle to the left. The upper dotted lines show the changed positions of said parts when the device indicates a change of direc-

tion to the right, and the lower broken lines indicate that the vehicle is about to come to a stop. The method of operation is obvious, and it will be observed that when the 5 lazy-tongs is fully extended in either of said directions, the pintle 7 is positioned at the bottom of the slot, so that the device is held releasably firmly in this extended position. The device, when fully collapsed, is 10 entirely withdrawn into the hollow of the housing 1, with the index-hand 19 swung over at a right angle to the lazy-tongs by the traction of the link 17 during the collapsing of said lazy-tongs.

15 A spring-clip 22 may be mounted on the housing 1, and have a boss 23 to releasably center and engage a hole or depression 24 in the lever 8 to secure the latter against displacement when the lazy-tongs is in its 20 upwardly inclined position.

As the outer edge and top of the index part 19 are closed by the connecting part 20, when collapsed into said housing, the lazy-tong members are protected thereby from 25 moisture or dust, while the index is strengthened in its structure. As the lazy-tong members are made from thin metal, when the housing 1 is mounted without a closed car, these members if sufficient in number allow the index to be brought up close 30 to the car when the lazy-tongs are collapsed, in a vertical position, so that the device may be actuated from within the car.

When collapsed into the housing, the pintle 7 is positioned in the recess part 3 above the pivot 11, where the device is thus held against displacement by jarring movements of the car. Variations in the specific structures and arrangements of the parts of the 40 device illustrated are nevertheless included within the scope of the invention.

Having described my invention, what I claim as new, and desire to secure by Letters Patent, is:

45 1. In combination, supporting-means containing three-way guiding-means, and a signaling-device mounted movably in said supporting-means and guiding-means for extension therefrom in either of three directions.

50 2. In combination, supporting-means, having a trifid guideway a collapsible extensible signaling-device mounted thereon, and having a part slideable in said guideway for 55 permitting of selectively extending said device at different angles to the supporting-means.

3. In combination, supporting-means containing trifid slideways, a lazy-tongs pivotally mounted on said supporting-means and 60 having an eccentric projection slidably mounted in said slideways, a signaling-device mounted on the outer end of said lazy-tongs, and means operable manually for extensibly actuating the lazy-tongs to move it 65 selectively in any of said trifid slideways to vary its angle of direction relatively to said supporting-means and to hold it releasably in either of its extended or its collapsed relations. 70

4. In combination, a lazy-tongs, a hollow signaling-device open at one side and end with end elements of the lazy-tongs inserted thereinto and movably connected thereto to be rocked in one direction when the lazy-tongs is collapsed, and a hollow housing, the 75 other end of said lazy-tongs having one member pivoted within said housing and means operative to cause the lazy-tongs to be extended from or retracted to the housing, the signaling-device when the lazy-tongs is collapsed being received completely 80 within the hollow of said housing with the closed end and side of said signaling-device positioned respectively upwardly and outwardly. 85

5. In combination, lazy-tongs, a hollow housing having three slideways converging to a medial common part, the pivotally-connected members of one end of said 90 lazy-tongs being respectively pivoted within the housing, and slidably mounted in said slideways to permit of extending the lazy-tongs in different directions, and a signaling-device having pivotal and linked 95 connections with the pivotally-connected members of the other end of the lazy-tongs, said device being a housing comprising spaced plates closed at one side and end, and said device being completely received 100 within said housing when the lazy-tongs is collapsed.

6. In combination, supporting-means, a collapsible extensible signaling-device mounted thereon, a three-way cam, said 105 device having a part slideable along said cam for selectively extending said device at either of three angles to the supporting-means, and releasable securing means for holding said device when extended at any 110 of said angles.

Signed at Waterloo, Iowa, this 21st day of October, 1921.

WALTER O. WILLE.
